UNITED STATES PATENT OFFICE.

WILLIAM FORBES WITTICH, OF CODY, WYOMING.

DESIGN FOR A CHAIR.

No. 37,666.

Specification for Design.

Patented Nov. 14, 1905.

Application filed August 30, 1905. Serial No. 276,459. Term of patent 14 years.

To all whom it may concern:

Be it known that I, WILLIAM FORBES WITTICH, a citizen of the United States, residing at Cody, in the county of Big Horn and State of Wyoming, have invented a new, original, and ornamental Design for a Chair, reference being had to the accompanying drawings.

I claim—

The ornamental design for a chair, as shown.

WILLIAM FORBES WITTICH.
